US00D909628S

(12) **United States Design Patent** (10) Patent No.: **US D909,628 S**
(45) Date of Patent: **** Feb. 2, 2021**

(54) **FILAMENT**

(71) Applicant: **Aladdin Manufacturing Corporation**,
Calhoun, GA (US)

(72) Inventors: **Maarten Meinders**, Dalton, GA (US);
Paul Pustolski, Newark, DE (US)

(73) Assignee: **Aladdin Manufacturing Corporation**,
Calhoun, GA (US)

(**) Term: **15 Years**

(21) Appl. No.: **29/665,282**

(22) Filed: **Oct. 2, 2018**

Related U.S. Application Data

(63) Continuation of application No. 29/583,406, filed on
Nov. 4, 2016, now Pat. No. Des. 841,838.

(51) LOC (13) Cl. **26-04**

(52) U.S. Cl. **D26/2**

Curfman LLC

(57) **CLAIM**

The ornamental design for a filament, as shown and
described.

DESCRIPTION

FIG. 1 is a perspective view of a first embodiment of our
new design;

FIG. 2 is a front view of the design shown in FIG. 1, the rear
view being a mirror image of the front view;

FIG. 3 is a left side view of the design shown in FIG. 1, the
right side view being a mirror image of the left side view;
FIG. 4 is a top view of the design shown in FIG. 1;
FIG. 5 is a bottom view of the design shown in FIG. 1;
FIG. 6 is a perspective view of a second embodiment of our
new design;

FIG. 7 is a front view of the design shown in FIG. 6, the rear
view being a mirror image of the front view;

FIG. 8 is a left side view of the design shown in FIG. 6, the
right side view being a mirror image of the left side view;
FIG. 9 is a top view of the design shown in FIG. 6;
FIG. 10 is a bottom view of the design shown in FIG. 6;
FIG. 11 is a perspective view of a third embodiment of our
new design;

FIG. 12 is a front view of the design shown in FIG. 11, the
rear view being a mirror image of the front view;

FIG. 13 is a left side view of the design shown in FIG. 11, the
right side view being a mirror image of the left side view;
FIG. 14 is a top view of the design shown in FIG. 11;
FIG. 15 is a bottom view of the design shown in FIG. 11;
FIG. 16 is a perspective view of a fourth embodiment of our
new design;

FIG. 17 is a front view of the design shown in FIG. 16, the
rear view being a mirror image of the front view;

FIG. 18 is a left side view of the design shown in FIG. 16, the
right side view being a mirror image of the left side view;
FIG. 19 is a top view of the design shown in FIG. 16; and,
FIG. 20 is a bottom view of the design shown in FIG. 16.
The break lines are shown to indicate indeterminate length.

1 Claim, 20 Drawing Sheets
